UNITED STATES PATENT OFFICE

2,414,615

COIN PURSE

George Slotkin, St. Louis, Mo.

Application April 25, 1944, Serial No. 532,627

1 Claim. (Cl. 150—32)

1

This invention relates to a coin purse and has for the primary object the provision of a device of this character which will be compact, extremely easy to insert in a pocket of a garment and to assume only a minimum amount of space therein and has a maximum number of parts, all of which except one are closed by flaps to prevent the coins from accidentally falling therefrom and a pair of the flaps having separable fasteners for normally maintaining them closed and they in turn retain the other flaps closed.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation, partly in section, illustrating a coin purse constructed in accordance with my invention.

Figure 2 is a sectional view taken on the line 2—2 of Figure 1.

Figure 3 is a sectional view taken on the line 3—3 of Figure 1.

Figure 4 is a plan view illustrating the blank from which the purse is constructed.

Figure 5 is a sectional view similar to Figure 2 showing the purse spread and illustrating the compartments thereof.

Referring in detail to the drawing, the numeral 5 indicates the body of the purse constructed of leather or of any other material suitable for the purpose. Formed in the body are compartments 6, 7, 8, 9 and 10. The compartment 6 is arranged innermost of all of the other compartments, while the compartments 7 and 8 are arranged on opposite outer sides of the compartment 6 and the compartments 9 and 10 are arranged on opposite outer sides of the compartments 7 and 8.

The compartments 6, 7 and 8 open through one edge portion of the body 5. The outer side walls of the body and which form the outer walls of the compartments 9 and 10 have portions cut therefrom by a slitting of the walls either on an arcuate or other curved line, as shown, or on a line of other suitable shape to form flaps 11 and entrances 12 to said compartments 9 and 10 as will be later more specifically described. The material of the body 5 which forms the walls to the compartment 6 as well as the inner walls to the compartments 7 and 8 has integral therewith flaps 13 which are somewhat larger and

2

fold over and cover the flaps 11 to retain the latter in a position of closing the mouths 12. The flaps 13 are provided each with a member of a separable fastener 14 which when connected to the companion member on the complementary wall portion secures the flaps 13 in closed position. Therefore, it will be seen that all compartments except the compartment 6 are closed by flaps to prevent coins and the like from slipping from the compartments 7, 8, 9 and 10 during the handling of the purse.

Whenever the flaps 13 are freed access to the compartments 7 and 8 may be had through one edge portion of the body 5 of the purse. Also, during the time the flaps 13 are freed and lifted, the flaps 11 may be easily lifted to give access to the compartments 9 and 10 through the entrances 12 arranged in opposite side walls of the body of the purse.

20 The compartment 6 while opening outwardly through the same edge of the body of the purse as the compartments 7 and 8, may be employed to receive cards or the like and even folded bills, yet this compartment is not primarily intended for the last mentioned use.

25 The body 5 is of substantially triangular shape and the various compartments are of a like shape as to the finished article, and so is the blank from which the article is formed, of a similar shape (see Figures 1 and 4). The free edges of the flaps 13 are curved at one corner thereof, as at 13', so that when said flaps are folded on each side of the body, the flaps will lie within the edges of the body to give the latter a neat appearance. The body being of triangular shape will facilitate the insertion thereof in a pocket of a garment as the apex of the body on the insertion thereof in the pocket leads into the pocket greatly assisting in the insertion of the body of the purse in the garment pocket.

30 35 40 Also the body being of the shape specified will take up a minimum amount of space within the garment pocket and if arranged in a side pocket of trousers will be found to readily conform to this type of pocket so as not to cause the trousers to bulge or sag.

The construction of the purse heretofore described and shown in the drawing is made from a blank 15, as shown in Figure 4, and requires only one row of stitching indicated by the character 16 (see Figure 1), consequently simplifying the making of the purse and permitting the blank thereof to be stamped from a sheet of material. The general outline of the blank 15 is 45 50 55 substantially triangular in shape and is provided

with a slot 17 extending inwardly from the apex for a selected distance. Further, the blank 15 adjacent the inner end of the slot 17 is provided with arcuate shaped cuts 18 which form the flaps 11 and the entrances 12. The blank is folded on the lines A, B, C, D, E and F. It will be seen by referring to Figure 4 that the fold lines are so arranged that they provide therebetween individual triangular shaped portions. Also the opposite longitudinal edges of the slot 17 cooperate with the fold lines in forming triangular shaped portions.

The portions of the blank outwardly of the fold lines A and E form the flaps 13.

One of the various ways in which the blank may be folded is that the blank is folded upon itself on the fold line F. This brings the triangular shaped portions lying between the fold line F and the slot 17 to overlie the triangular shaped portions lying between the fold lines F, B, C and D. The blank is then again folded on the fold lines B and D bringing the triangular shaped portions defined by the fold lines A, B, D and E to overlie the triangular shaped portions of the blank defined by the slot 17 and the fold line F. The blank is then folded on itself on the fold line C with the triangular portions containing the slits 18 and flaps 11 outward and stitched together by a single row of stitching, heretofore referred to by the character 16, retaining the blank in substantially triangular formation with the flaps 11 and 13 free for swinging movement on the lines A and E either to open or close the compartments 7, 8, 9 and 10.

Thus it will be seen that a very efficient coin purse has been provided, one which may be stamped in a single operation from a sheet of material and simply folded to form a multiplicity of compartments with the body of the purse taking on a substantially triangular shaped formation.

While I have shown and described the preferred embodiment of my invention, it will be understood that minor changes in construction, combination and arrangement of parts may be made without departing from the spirit and scope of the invention as claimed.

Having thus described the invention, what I claim is:

A purse blank made of a single piece of material, substantially triangular in form and of predetermined size, said triangular blank having rounded corners at its base and being slotted for substantially half the distance from its apex to its base and extending perpendicularly to the base, the major part of the blank in the region of the base portion being foldable upon an inner line parallel to the base line and upon outer lines and a central line, the said outer and central lines extending perpendicularly to the base line, whereby said parallel and perpendicular lines define two rectangles, said central perpendicular line at its inner end joining the inner end of the slot of said slotted portion of the blank; said blank being also foldable upon diagonal lines extending from the base end of said central perpendicular line and running to the diagonally opposite corners of the said rectangles, the portions of the blank within the two inner adjoining triangles defined by the diagonal lines of folding being provided with slits to produce like flap portions contiguous to the inner parallel line of folding, the body of the blank, when folded along the said lines of folding and including the two triangular portions defined by the slitting of the blank inwardly from its apex to the parallel inner line of folding, producing a coin purse of substantially triangular shape and having a plurality of separate compartments opening outwardly through one common edge portion of the purse body, a central compartment opening without any closure and the substantially triangular rounded portions of the blank outside of the two outer perpendicular folding lines forming flaps for covering and uncovering, respectively, the openings of each companion pair of compartments on opposite sides of the central compartment of the purse and the flaps produced by said slits each providing an individual entrance to the outer compartment of each pair of compartments of the purse.

GEORGE SLOTKIN.
